SPAGHETTI WRAPPING MACHINE AND METHOD
Rene J. Gaubert, Oakland, Calif., assignor to Triangle
Package Machinery Company, Chicago, Ill., a corpora-
tion of Illinois

Filed Dec. 31, 1959, Ser. No. 863,313
11 Claims. (Cl. 177—1)

This invention relates to a wrapping machine and method generally, and more particularly it relates to those machines and methods which may be used for wrapping elongated rigid and semi-rigid materials.

In the past various methods and machines have been used for carrying out large scale packaging operations. Considerable progress has been made in machines for packaging such items as candy, nuts, beans and the like wherein a preformed bag is filled with a predetermined amount of the product and is later sealed. Many products however do not lend themselves to the bag filling type of procedure. This is especially true of elongated rigid and semi-rigid products such as spaghetti, straws, carrots, celery, licorice sticks and the like. The common procedure for such articles as these is to weigh the contents on balancing scales, add or remove until the desired weight is obtained, fill a bag and close it by hand. A conveyer belt is, at times, used to carry the product to several hand operated stations. But even with the use of a conveyer belt, no appreciable reduction of hand operation is accomplished.

Due to the nature of certain elongated rigid products as spaghetti, macaroni and the like, machine packaging is particularly difficult. Bulk spaghetti as received from the manufacturer is not only rigid and brittle but due to the manufacturing processes, many of the spaghetti sticks have partial loops at one end. Also the bulk spaghetti includes pieces of various lengths having sharp points. Moreover, bulk spaghetti is not usually found in an orderly array. The various sticks are usually skewed and interlinked with one another. For these reasons, automatically pouring spaghetti into a bag has been found extremely impractical, and has not satisfactorily been accomplished. For the same reasons, measuring or weighing of particular quantities of spaghetti automatically has not been practical. Consequently the automatic machine packaging of spaghetti and macaroni consumer products has had little or no progress in the art beyond the manual operations.

Other elongated rigid products as mentioned above have met with similar difficulty in the field of automatic packaging. In an effort to save labor in the packaging of such products, several of the operations have been mechanized to provide a machine for delivering measured amounts of the product.

It is therefore a general object of the present invention to provide an automatic wrapping machine which will overcome many of the disadvantages of prior wrapping machines and methods.

It is a more particular object of this invention to provide an automatic wrapping machine for wrapping elongated rigid and semi-rigid products which will separate a predetermined quantity of the product to be packaged.

It is another object of this invention to provide an automatic packaging machine of the above character wherein a predetermined volume of a product is separated from a bulk source and small amounts of the product are added until a predetermined weight is attained.

It is a further object of this invention to provide an automatic packaging machine for products of the above-mentioned nature which will produce a neat, tightly wrapped compact package.

It is another object of this invention to provide a fully automatic wrapping machine, the automatic cycle

2

of which includes cutting individual sheets from a roll of suitable material such as cellophane or polyethylene, and automatic wrapping of the product into the sheets.

It is a further object of this invention to provide an automatic wrapping machine having means for automatically sealing the package after it is wrapped.

It is still another object of this invention to provide an automatic wrapping machine which provides means on the package to facilitate opening after it is wrapped.

These and other objects and features of the invention will become more clearly apparent upon reading of the following description in which the preferred embodiment has been illustrated in conjunction with the accompanying drawing.

Referring to the drawing:

FIGURE 32a is an elevational view and partial section taken along the line 32-32 of FIGURE 33 showing the end fold and seal unit used in accordance with the present invention;

FIGURE 32b is an elevational view of the bottom folder and seal unit 721;

FIGURE 33 is a plan view and partial section of the end fold and seal unit;

FIGURE 34 is a partial side elevational view of the machine showing the cams for operating the end fold and seal unit;

FIGURE 35 is a partial plan view of the machine showing the cams for operating the end fold and seal unit;

FIGURE 36 is a timing chart showing the timing of the various mechanisms in the wrapper feed and cutting unit;

FIGURE 37 is a chart showing the timing of the hopper unit;

FIGURE 38 is a chart showing the timing of the longitudinal fold and tack seal unit;

FIGURE 39 is a chart showing the timing of the longitudinal seal unit;

FIGURE 40 is a chart showing the timing of the end fold and seal unit; and

FIGURE 41 is a schematic wiring diagram of the machine.

Referring to FIGURE 1 of the drawing, the machine illustrated includes a paper feed unit 11 which serves to feed and cut wrapping material to proper length, a conveying unit 13 which serves to carry the wrapping material and the product to be wrapped to the various stations of operation. A hopper unit 15 which delivers a proper amount of the product to the conveying unit, and a longitudinal fold unit 17, which folds the wrapping material into a longitudinal tube are included. Also included are a longitudinal seal unit 19 which seals the formed tube, an end seal unit 21 which folds and seals the ends of the tube and a dispensing unit 23.

The operation of each of the above mentioned units may best be described in conjunction with the schematic diagram of FIGURE 2. The conveyer unit 13 includes an endless chain 25 which travels about sprocket gears 105, 107, 111 and 113 (FIGURES 1, 4 and 15). Mounted on the endless chain 25 are a series of open ended buckets 31 which are equally spaced about the chain 25. In operation the chain travels intermittently in the direction shown by arrows in FIGURE 1. The spacing of the various units is related to the intermittent motion of the chain 25 such that the buckets travel from one station to the next, hesitating at the various stations.

The paper feed unit 11 serves to transform a roll of material such as wrapping paper, cellophane or the like as shown at 38 (FIGURE 1) into sheets of predetermined length as shown at 35 (FIGURE 2). As a bucket 31 passes by the paper feed unit 11 (FIGURE 1), a sheet of material 35 is laid over the open face of the bucket and is held in place by the fingers 95 and 97 (FIGURE 2) by means to be described hereinafter.

The hopper unit 15 (FIGURE 1) serves to separate a predetermined portion 37 of the product to be wrapped from bulk storage. The predetermined amount is lowered to the sheet of paper 35 and into the bucket 31 as shown at B and C in FIGURE 2, thereby conforming the sheet to the shape of the bucket.

It will be noted that the end of the spaghetti 37 extends slightly beyond the edge of the bucket 31. This is to facilitate folding and sealing of the ends at a later station by

affording a surface to seal against. Prior to and during the positioning of the spaghetti in the bucket, the edge of the paper 35 is retained along the side of the bucket. At a time after the spaghetti has been placed in the bucket and the material 35 is conformed to the sides of the bucket the edge 35 may be released as shown at D.

The bucket is then moved to the next station, the side fold unit 17, wherein the sheet 35 is wrapped about the product and tack sealer as shown at 41 is applied. The paper is folded by means of fingers to be described hereinafter and is tack sealed while the fingers retain the paper in its folded position. The tack seal 42 serves to retain the sheet in its folded position while the bucket is moved to the next station.

At the longitudinal seal unit 19 (FIGURE 1) the sheet 35 is sealed along its entire length over the tack seals 42 as shown at 43 (FIGURE 2).

The package then proceeds as an open ended tube to the end seal unit 21 (FIGURE 1). This unit serves to fold the ends of the wrapper to overlie the product and to seal the wrapper in that position. Views F, G, H and I of FIGURE 2 show the package at this unit. At the first operation the fingers 50 fold the sides of the package as shown in view F and thereby provide a top flap 55 and a bottom flap 56. While the fingers 50 are still in position, the top folder 52 sweeps by the top flap 55 and lays it over the previously folded sides to hold the package as shown in view G in FIGURE 2. At this point the side folding fingers 50 are removed and the bottom folding unit 54 is brought upward bringing with it the bottom flap 56 as shown in view H. The top flap folder is then removed after which the bottom flap fold unit 54 is moved inward toward the package to press the completed fold. The bottom fold unit 54 may be a heater which when the unit is pressed against the package will serve to seal the ends thereof. The completely wrapped and sealed package is then moved to the dispensing unit 23 (FIGURE 1) and is there placed upon a conveyor belt to be carried to a convenient location for boxing.

Although the embodiment shown in FIGURES 1 and 2 has a particular number of named stations or units, additional units may easily be added. It will be noted that space is available to add another unit in the embodiment of FIGURE 1 between the hopper unit 15 and the longitudinal seal unit 17. As shown in FIGURE 1 the overall machine is constructed in easily separated portions. The separable portions are the input section 45, the intermediate section 47, and the discharge section 49. To utilize additional stations it is merely necessary to add additional intermediate sections, each of which in the embodiment shown is capable of handling two stations. Additional stations which may be feasible are such as one to insert a label within the package or additional sealing stations may be added to accomplish a longer and even tighter seal to those skilled in the art upon reading the following description.

Bucket and Bucket Drive

Referring particularly to FIGURES 1, 3 and 4, a bucket 31 is shown. The bucket comprises an open ended and open topped like member having a bottom 57, front side 59 and rear side 61. The sizes of the buckets may be varied to fit the individual product and the amount of which is to be packaged. The front side of the bucket is provided with openings 63, 65, 67 and 69 while the rear side is provided with openings 71, 73, 75 and 77. It will be noted that the openings 63 and 71, and the openings 69 and 77 are in registry while none of the other openings are so disposed. As will be described hereinafter, openings 65, 67 and 69 are provided to admit forward folding fingers of the longitudinal fold unit 19 (FIGURE 1). Likewise the openings 71, 73 and 75 are utilized to admit rear fingers of the same unit. The openings 63 and 71, and 69 and 77 which are in registry with

each other are utilized at the end seal unit to accept a pressure arm to maintain the package tightly in position while the end sealing operations are in progress.

The bottoms 57 of the buckets are attached to bucket bars 79 by screws or other convenient means. One end of each bucket bar is bored through at 81 while the other end has a longitudinal slot 83 therethrough. The bucket bars 79 are clamped to the bucket shafts 85 through the bore 81. The slots 83 provide pivotal and sliding motion to the shaft 87. The shafts 85 and 87 are pivotally mounted in spaced lengths of the bucket drive chains 25 (FIGURE 2).

A shaft 93 extends between the bucket bars 79 in close proximity to the front side 59 of the bucket. Paper hold-down arms 95 and 97 are secured about the shaft 93, and are resiliently urged against the front side 59 of the bucket by means of a torsional spring 99. Also affixed to the shaft 93 is a cam arm 101, depending downwardly from the shaft 93. At the lower end of the cam arm 101 is a cam surface 103 which is utilized, in the manner to be hereinafter described, to release the paper hold-down arms 95 and 97.

The location of the various buckets on the chains 89 and 91, is determined by the spacing of the various stations of the machine. The bucket spacing should be equal to the minimum spacing between operating units and the spacing between the various operating units should be an integral multiple of this minimum distance. With such an arrangement the various stations may operate in conjunction with several buckets simultaneously.

Chains 25 are endless and extend substantially the full length of the machine. Sprocket gears 105 and 107 (FIGURES 1 and 15) rotate about a shaft 109 at the input end of the machine. Sprocket gears 111 and 113 (FIGURES 1, 4 and 6) are affixed to the torque shaft 115 for simultaneous rotation at the discharge end of the machine.

Referring simultaneously to FIGURES 3, 5 and 6, a prime mover such as motor 117 is affixed to the frame 119 of the discharge section 49. A pulley 121 is attached to the shaft 123 at one end of the motor. A belt 125 transfers the motion of the motor 117 to a pulley 127. The pulley 127 is affixed to the shaft 129 of a clutch assembly 131. The output shaft of the clutch assembly 131 is connected through a speed reducing gear box 133. The output shaft of the speed reducer is connected to a Geneva arm 135 which is intermeshed in a Geneva wheel 137. The Geneva wheel 137 is affixed to a torque shaft 139 which carries thereon a drive sprocket 141. A drive chain 143 is intermeshed with the drive sprocket 141 and passes about idler sprockets 145 and 147 to the sprocket 149. The sprocket 149 like the sprockets 111 and 113 is rigidly affixed to the shaft 115. Thus it is seen that intermittent motion of the bucket chain 25 is accomplished by the use of a Geneva movement.

Also affixed to the output shaft of the speed reducer 133 is a timing sprocket 151. A chain 152 is intermeshed with the timing sprocket 151 and the sprocket 153 on the torque tube 155. At the opposite end of the torque tube 155 is a sprocket 159, rigidly affixed thereto. A chain 161 is intermeshed with the sprocket 159 and passes the idler 160 to drive the sprocket 163.

Referring to FIGURES 3 and 35 it is seen that the motion of the sprocket 159 is transferred to the sprocket 163 through the chain 161. Affixed to a common torque tube 165 with the sprocket 163 is an additional driving sprocket 167. Enmeshed with the driving sprocket 167 is the machine timing chain 169. Referring again to FIGURE 1 it is seen that the chain 169 passes the tensioning idler 171, and drives cam drive sprocket 173. Another chain driven by a second sprocket on the shaft with sprocket 173 passes a second tensioning idler 175 and additional cam drive sprockets 177 and 377. It will be noted that for additional stations, cam drive sprockets may be added at the locations provided such as at 179.

It will be seen then that the machine timing chain 169 provides continuous motion so long as the motor 117 and the speed reducing gears 133 are in operation. As will be described hereinafter, the machine timing chain is utilized to activate the various stations to perform their particular operations at the particular time desired so that the overall machine will operate with a continuous flow of the packaged product. The time spent at each station is equal, consequently each station may operate on a different package at the same time to perform its individual function.

Referring to FIGURES 14 and 15, means in addition to the Geneva drive is shown to assure that the buckets 31 are stopped in proper relationship with the various units. An arm 180 having a dog 184 rotates about the shaft 182. A cam arm 186 having a cam surface 188 is affixed to the arm 180 for rotation therewith. Secured to the sprocket 105 for simultaneous rotation about the cam shaft 109 is a wheel 190 in registry with the dog 184. The wheel 190 has a pair of diametrically opposed openings 192. A cam wheel 194 is affixed to the cam shaft 109 and is in registry with the cam surface 188.

Upon rotation of the cam wheel 194, the cam surface 188, and consequently the dog 184, is periodically raised out of the openings 192. With the dog free from the opening 192, the wheel 190 and consequently the sprocket 105 and its associated chain 25 is free to rotate. By proper timing of the cam wheel 194, the sprocket 105 can be periodically stopped at a predetermined rotation. The rotation is selected to cause the buckets 31 to stop at the center of the individual operating units.

As will be noted from FIGURE 1, each of the sections 45, 47 and 49 are approximately of the same length. Additional intermediate sections which may be desired may have the exact length as the intermediate sections 47 as shown. The location of stations on the intermediate section 47 is such that one station is centered at the center of section 47 while additional sections may be centered at the opposite ends of section 47. Consequently the longitudinal seal unit 19 is centered at the intersection of the intermediate section 47 and the discharge section 49. The end seal unit 21 is located on the discharge section 49 at a distance from the intermediate section 47 equal to half the length of the intermediate section. The location of the hopper unit 15 is likewise spaced from the intermediate section 47 a distance half the length of the intermediate section. Consequently the input section 45 and the discharge section 49 are not necessarily equal in length to the intermediate sections 47 but may be either longer or shorter. The only requirement being that the spacing of the units 15 and 21 be from the intermediate section 47 a distance one-half the length of the intermediate section.

It will be obvious to those skilled in the art that the particular arrangement mentioned above may be altered in various ways. The embodiment shown is merely a preferred design. The principle of the invention may be equally well carried out with the various sections being capable of handling only one individual unit or station or it may be such that the individual sections may be capable of handling three, four or even more individual stations. It is likewise within the scope of this invention to provide a machine having only a single section whereon all of the stations are located.

It is preferred that the spacing of the stations be equal, or that the spacing between any two individual stations be an integral multiple of the spacing between the two closest stations. The spacing of the buckets 31 on the bucket chain 25 is determined by the spacing of the stations themselves, spacing of the buckets being equal to the closest spacing between two individual stations.

Paper Manipulation

The paper feed unit 11 as shown in FIGURE 1 is shown more in detail in FIGURES 7 to 15. Brackets

181 and 183 are attached at the end of the input section 45 by the use of bolts or other convenient means. The upper ends of the brackets 181 and 183 are bored to receive the shaft 185. Additional brackets 187 and 189 are attached to the brackets 181 and 183, respectively and are bored to receive the shaft 191. The shafts 185 and 191 are free to rotate within their respective bores, and extend through the brackets 181 and 187. Adjustably secured on the shaft 185 are the hubs 193 and 195. Likewise the hubs 197 and 199 are attached to the lower shaft 191. Also rigidly attached to the shafts 185 and 191 are the brake drums 201 and 203 respectively.

A shaft 205 is pivotally connected between the sides of the input sections 45. Secured to the shaft 205 are the arms 207, 209, 211 and 213. The arm 211 may if desired be an extension of the arm 209. Arms 207 and 209 extend parallel from the shaft 205. A roller 215 is pivotally mounted between the ends of the arms 207 and 209. A spring 217 is connected between an extremity of the arm 211 to a point on the input section frame below the arm 211. The spring 217 thereby tends to urge the arms 207, 209, 211 and 213 clockwise about the shaft 205 as viewed in FIGURE 7.

A primary brake rod 219 is pivotally mounted at the end of the arm 213. Brake shoes 221 and 223 are pivotally mounted to the brackets 181 and 187 at 225 and 227 respectively. Each of the brake shoes 221 and 223 includes an extension 229 and 231 respectively. The extension 229 is provided with a bore through which the brake rod 219 slides freely. A collar 233 is adjustably secured about the brake rod 219, and a compression spring 235 is located about the rod 219 between the extension 229 and the collar 233.

Pivotally attached to the brake drum extension 229 is a secondary brake rod 237 which extends through the brake shoe extension 231 similar to the rod 219 through the brake shoe extension 229. The collar 239 is adjustably mounted on the rod 237 and a spring 241 is located between the collar 239 and the extension 231.

Thus it is seen that the spring 217 tends to urge the arm 213 upward in a clockwise motion about the shaft 205 while a downward force on the arms 207 and 209 tend to force the brake shoes 221 and 223 downward to the brake drums 201 and 203. The amount of force required on the shafts 207 and 209 to cause braking contact on the drums 201 and 203 may be adjusted by movement of the collars 233 and 239 on their respective brake rods 219 and 237.

It is often desirable in packaging various products to utilize two thin wrapping films rather than one relatively thick film. Using multiple film not only provides a better and stronger finished package but may be more economical if the finished package is to contain a trademark, description or other matter printed thereon. Since the cost of printed wrapping paper is usually affixed by weight rather than the actual amount of printing, the printed matter is considerably cheaper on a thin film than on a film thick enough to provide a satisfactory completed package. Rolls of such film may be rotated simultaneously about the shafts 185 and 191 on the respective hubs 193, 195, 197 and 199.

Hubs 193 and 197 are provided with rims 243. Adjustment wheels 245 engage the rims 243 and are attached to the shafts 247. The shafts 247 are threaded into the brackets 281 and 287 and have handles 249 affixed to their ends opposite the adjustment wheels 245. This mechanism may be used to adjust the distance between the hubs to provide variations in the width of the wrapping material core.

Also attached to the input section frame 45 is the paper measuring and cutting assembly 251 shown in more detail in FIGURE 9. The paper measuring and cutting assembly 251 is adjustably connected to the input section frame 45 by means of elongated slots 253 in the brackets 255 (shown only one one side of the ma-

chine). Mounted on the brackets 255 is a roller assembly 257 including a stationary axis roller 259 and a floating roller 261. The floating roller 261 rotates in bearing blocks 263 which may slide vertically in the roller guides 265. The guides 265 and the roller 261 are resiliently urged downward onto the roller 259 by means of the roller springs 267.

As may be better seen in FIGURES 10 and 11, the shaft 271 of the stationary roller 259 has a magnetic clutch 269 affixed at one end. The driven member of the clutch (not shown) is affixed to the shaft 271. The drive sprocket 273 is freely rotatable about the shaft 271 and is selectively coupled by magnetic energy to the driven member of the clutch. The drive sprocket 273 is driven by the paper feed chain 275. One end of the chain 275 (FIGURE 14) is connected to a pin 277 by a spring 279. The chain 275 extends from spring 279 about an idler sprocket 281 freely rotatable about the shaft 205, the drive sprocket 273, another idler sprocket 283 to the arm 285 (FIGURE 15). The arm 285 is freely rotatable about the shaft 287. The shaft 287 is mounted at one end of an eccentric arm 289. Adjacent to the arm 289 is a member 291, affixed to the shaft 109 which engages the timing sprocket 177 at the opposite side of the machine. A slot 297 is formed in one end of the member 291 and the shaft 287 extends therethrough. Arm 289 is slidably engaged with the arm 291 by means of an adjustment screw 299 and nut 300. The slot 297 retains the shaft 287 in line with the adjustment screw 299. It is seen therefore that the radius of rotation of the shaft 287 about the shaft 109 may be varied by adjustment of the screw 299. Consequently, the length of the oscillating stroke of the chain 275 may be adjusted by the screw 299. In operation, then, the drive sprocket 271 of the magnetic clutch 269 rotates a preselected number of turns in an oscillating manner. Dependent upon the timing, to be described hereinafter, the magnetic clutch may be engaged to cause a roller 259 to turn a predetermined portion of the cycle of the drive sprocket 273.

In normal packaging operations, the wrapping paper will usually have some printed information thereon. At least to the extent of the name of the product and the quantity packaged. Additionally for the purpose of automatic operation of this machine, there may be printed on the paper in prescribed location a marking spot. The marking spot should be generally opaque relative to the rest of the paper, but need not be entirely opaque. The marking spots so described should be arranged on the paper at intervals dependent upon the length of the paper required to provide the desired package. For simplicity in operation, one marking spot for each length of paper is adequate.

With the marked paper in mind, I provide an electric eye comprising a light source 301 (FIGURE 10) and a photocell 303. The electric eye assembly is adjustably mounted in brackets 305 and 307 (FIGURE 9) whereby opaque marking spots at various locations on the paper may be detected. The electric eye is connected such that it is inoperative during the first portion of a cycle while wrapping material is being fed. After a substantial portion of the wrapping material has been fed, the electric eye is actuated whereby upon the passage of light to the photocell 303 the magnetic clutch 269 remains engaged. Upon the elimination or the reduction in the amount of light at the photocell 303, the magnetic clutch 269 is disengaged and braked thereby stopping the roller 259. By means to be described hereinafter, the magnetic clutch 269 will remain disengaged until the next cycle of the timing chain begins.

With this manner of operation, the flow of paper through the rollers 259 and 261 from the rolls about the shaft 185 and 191, is intermittent. Paper rolls are usually heavy having a large amount of inertia and upon stopping the flow of paper through the rolls 259 and 261,

the rolls about the shaft 185 and 191 may continue to rotate. In order to prevent this, paper is passed first over an idler roller 309 (FIGURE 7), under the roller 215 and over the idler roller 311. The arms 207 and 209 described above are of such mass that their weight overcomes the action of the spring 217 and forces the brake shoes 221 and 223 onto their respective drums 201 and 203 unless there is an upward tension on the roller 215. Upon release of the magnetic clutch 269, the paper will cease to flow past the rollers 259 and 261 and the paper represented as A in FIGURE 7 will remain stationary. The paper represented at B however will continue to flow due to the inertia of the rolls. Consequently the loop of paper represented by the sections A and C will lengthen and the roller 215 will be lowered to such an extent that the shoes 221 and 223 will engage their respective drums 201 and 203 thereby preventing further rotation of the rolls of paper on the shafts 185 and 191.

Referring to FIGURES 10 and 11, it will be noted that the rollers 259 and 261 are grooved at 313. Located in these grooves and attached to the frame of the roller assembly 257 are paper guide and separators 315. As viewed in FIGURE 9, the guides at the entrance portion of the rollers follow the contour of the rollers themselves whereas on the exit side of the rollers they extend in a straight line to the right. Upper paper guides 315 extend to the right and abut an upper knife edge 317. The upper knife edge is affixed to the mounting and cutting assembly 251. Also stationary with respect to the mounting and cutting assembly is a blade guide 319 which is flush with the upper knife edge 317. Referring to FIGURE 13, a movable knife edge 321 overlies the blade guide 319 and resiliently presses against the guide, by means of a spring 323. A pair of arms 325 extend downward from the movable blade 321. Studs 327 are located at the end of each of the arms 325 and engage one end of the arms 329 which are affixed to the shaft 333. One end of a link 335 is pivotally attached to the shaft 333, the other end being pivotally engaged with the link 337.

Referring to FIGURE 14, the link 337 is frictionally engaged in the cam driven tube 339, by the spring urged shoe 341. At one end of the cam driven tube is an elongated slot 343 fitted over the shaft 295. Cam followers 345 and 347 are located at opposite ends of the elongated slot 343. Cams 349 having extended cam surfaces 351 are rigidly affixed to the shaft 109, which rotates with the movement of the machine timing chain 169. As will be apparent from the drawing in FIGURE 14, one rotation of the shaft 109 will cause a reciprocating horizontal motion of the cam driven tube 339. As viewed in FIGURE 9, motion to the right of the tube 339 will cause motion of the link 337 and a counterclockwise rotation of the link 335 and arm 329 about the shaft 333. The counterclockwise rotation of the crank 329 forces the movable blade 321 upward to shear the paper which has previously been passed between the blades 317 and 321.

Before the paper is cut into the required lengths by the blades 317 and 321, it is passed through the guides 353 and 355 to overlie the front side 59 of the bucket 31 as shown in FIGURE 14. As shown in FIGURES 14 and 15 and previously described in connection with FIGURES 1, 3 and 4, the fingers 95 and 97 associated with the buckets 31 normally are urged against the front sides 59 thereof. However when the buckets 31 are in or are approaching the position shown in FIGURES 14 and 15, the cam arm 101 and cam surface 103 are in position adjacent the cam arm 357. The cam arm 357 is affixed to the cam shaft 109. As explained earlier the cam shaft 109 rotates in accordance with the timing chain thereby providing periodic movement of the cam arm 357.

Consequently, when in the location as shown in FIGURES 14 and 15, the cam arm 357 moves downward as viewed in FIGURE 15 thereby forcing the cam arm 101 downward and the fingers 95 and 97 upward. The upward movement of the fingers 95 and 97 permits the

overlying sheet of wrapping material 35 to fall between the front side 59 of the bucket 31 and the fingers 95 and 97. After the cam arm 357 rotates past the cam arm 101, the fingers 95 and 97 are free to be restored to their original position against the front side 59 of the bucket 31. At this point the sheet of paper 35 is resiliently restrained between the bucket and the fingers.

The Hopper Feed

Referring to FIGURES 16, 17, 18, and 19, the hopper unit or station 15 of FIGURE 1 is shown. The hopper serves to receive the product such as spaghetti from a bulk source, to separate it by volume, to adjust the weight of the separated amount, and to deliver the weighed amount into the bucket 31 at the hopper station. The timing of the hopper unit, like the other units in the machine, is controlled by the timing chain 169 which rotates the master hopper timing wheel 377 on the timing shaft 379.

As seen in FIGURE 17, the hopper unit assembly includes a main hopper 381 and a dribbler hopper 383. Both of the hoppers are maintained in constant vibration by suspension mountings 385 and 387 each of which are slightly oscillated about the studs 389 on the frame 391. The oscillation is accomplished by the arms 393 having an annular bearing 395 at one end thereof mounted about an eccentric 397 which rotates with the tube 399. As seen in FIGURE 18, power is supplied to the tube 399 by the motor 401 through the pulleys 403 and 405 and the belt 407. Thus it is seen that the hoppers 381 and 383 have a generally left to right oscillation due to the eccentric motion applied to the bearing 395. Also due to the circular path of the mounts 385 and 387 about the stud 389 a slight up and down oscillation is accomplished.

This oscillation of the hoppers 381 and 383 tends to pack the spaghetti or macaroni therein and to some degree to align the various sticks of the product with each other.

The hopper 381 is supplied with a barrier or baffle 409 which serves to allow a predetermined amount of spaghetti to pass therebelow. An additional movable baffle 411 serves to sense interruption of flow of the spaghetti as may be caused by the hopper 381 becoming empty. One end of baffle 411 rides upon the activator 413 of a microswitch 415 which may serve to either close an alarm circuit or to stop the machine altogether or both.

Referring to FIGURE 17, a first chute 438 is shown disposed below the hopper 381. The bottom of the chute 438 may be held closed by the intermeshed gates 439 which may be geared (not shown) to act symmetrically. As viewed in FIGURE 19, one of the gates 439 is affixed to a common shaft with the arm 440. A stud 441 on an arm 442 lies below and in registry with the arm 440 whereby upon upward motion of the arm 442 the gates 439 are closed. The arm 442 is affixed to a sprocket 443 freely rotatable about the shaft 444. A chain 445 is resiliently affixed at one end to stud 446 and on the other end to the cam follower 447. The cam follower 447 is slotted to receive the shaft 379 and has a stud 448 disposed adjacent a cam (the various cams on shaft 379 are illustrated only schematically and are generally nominated as 449) affixed to the shaft 379. Thus it is seen that upon rotation of the timing shaft 379 the gates 439 are periodically closed. Spring means (not shown) may be utilized to open the gates 439 at such times when the stud 441 is in its downward position.

Referring to FIGURES 17 and 18, a volumetric separator 450 is disposed adjacent the first chute 438 and is vertically movable with respect thereto. The separator includes a central finger 451 and outside fingers 452. The fingers are carried by and are slidable with respect to the guides 453. A slotted member 454 is secured to one end of each of the fingers 451 and 452. A bar 455 affixed to one end of the arms 456 is disposed within the

11

slots in the members 454. The other ends of the arms 456 are secured to a shaft 457. Also affixed to the shaft 457 is a sprocket 458 having a chain 459 wound thereabout and resiliently secured at 460 (FIGURE 19) on one end. The other end of the chain 459 is affixed to a chank arm 461 which is freely rotatable about the shaft 462. A cam surface 463 at the other end of the arm 461 engages a cam (illustrated as 449 generally) on the timing shaft 379. Thus it is seen that by rotation of the cam on the timing shaft 379 the fingers 451 and 452 periodically are withdrawn from the chute 438. The resilient mounting of the chain 459 at 460 is utilized to urge the fingers into the chute toward the left wall thereof as shown in FIGURE 17.

A continuous chain 464 passing about the sprockets 465 (FIGURE 18) is affixed to one of the fingers 452 at 466 to the other finger 452 at 467. Upon oscillation of the sprockets 465 the guides 453 associated with the fingers 452 are withdrawn from the center finger 451 and returned to the position shown in FIGURE 18 periodically. One of the sprockets 465 is slidably keyed to the shaft 468 having a spur gear 469 affixed to one end thereof. A rack 470, pivotally engaged at one end to a crank 471 engages the spur gear 469. The other end of the crank 471 is slotted to receive the stud 472 which rotates with the timing shaft 379. Rotation of the timing shaft 379 causes the rack to oscillate from left to right as viewed in FIGURE 16. Thus upon rotation of timing shaft 379, the fingers 452 are drawn to the center toward the fingers 451 and subsequently retracted.

Thus it is seen that the hopper 381 continually vibrates causing spaghetti contained therein to be continually packed and to travel past the baffles 409 and 411 into the chute 438. Timing of the machine is such that during this operation the gates 439 remain in their closed position and the fingers 451 and 452 are held in their withdrawn position. After sufficient time has elapsed for the chute 438 to fill, the fingers 451 and 452 are extended to the left into the chute as seen in FIGURE 16. The extension across the chute separates the spaghetti from the upper and lower section thereof. The separation is made more complete by the withdrawal of the fingers 452 to their outer extremities of travel. Consequently spaghetti which may be vertically skewed in the chute 438 is aligned and the volumetric separation defined by the fingers 451 and 452 is contained within the chute 438. While the fingers are still extended into the chute, the edge walls 476 (FIGURE 18) of the chute 438 are withdrawn away from the center by the cams 478 on the cam shaft 480. With the edge walls withdrawn, the gates 439 are opened. Thus it is seen that the spaghetti has freedom to fall into the next lower chute without obstruction from the chute 438 itself.

As mentioned above, the fingers 451 and 452 are vertically movable with respect to the chute 438. To this end the screw shafts 482 are threaded through the volumetric separation unit. The shafts 482 are connected for simultaneous rotation by means of sprockets and chain. Thus it is seen that upon rotation of one of the screw shafts by the handle 484, the entire volumetric separation can be raised or lowered with the sprockets 465 sliding along their respective shafts 468 in keyed relationship therewith. Consequently the fingers 451 and 452 may be adjusted to separate any desired volume limited only by the maximum volume of the chute 438. Moreover additional means are provided to raise and lower the volumetric separation unit as will be defined more particularly hereinafter.

Separation is followed by a weighing operation. The weight of the spaghetti separated by the volumetric separator is selected to be less than the standard weight and a dribble feed is utilized to bring the separated amount up to standard.

Certain products such as spaghetti change in shape and moisture content such that the weight of a predetermined

12

volume will vary. This variation may require a long dribbling time, at times sufficient to slow the operation of the machine.

In order to adjust for minor variations in the weight of the spaghetti being packaged, and to minimize the dribbling requirement, a fine automatic adjustment is provided. To this end the oscillating shaft 488 has a crank 486 affixed at one end thereof. The crank is connected to a plate 488 which is oscillated about the screw shaft 482 by means of a link 490. An arm 492 is centrally pivoted at one end of the plate 488. Links 494 are secured to the ends of the arm 492 and are connected to the solenoids 496. Thus it is seen that upon operation of either the solenoids 496, the arm 492 is rotated either clockwise or counterclockwise about its pivot point on the plate 488. Also affixed to the arm 492 are a pair of ratchet pawls 498a (only one shown) which are associated one with a left hand and one with a right hand ratchet wheel 498 (only one shown). Each of the ratchet wheels are secured to the screw shaft 482. Thus it is seen that when the arm 492 is in its counterclockwise position on the plate 488, the oscillation of the plate 488 will cause the shaft 482 to turn in one direction while the clockwise position of the arm 492 will cause the screw to turn in the opposite direction. The ratchet pawls 498a are held in contact with ratchet wheels 498 after the momentary pull of solenoid bypass over center spring (not shown). Means is also provided such as the handle 500 for maintaining the ratchet in a central or inert position whereby the handle 484 may be utilized to vary the position of the volumetric separator by hand.

Activation of the solenoids 496 is initiated by various timing switches to be explained hereinafter.

Referring to FIGURE 16, the scale and its associated chute is shown. The scale chute 502 is disposed directly below the first chute 438 and is held in place by the arms 506 and 508 pivoted at 510 and 512 respectively. The arm 508 has an extension 514 with a counter weight 516 affixed thereon. A dash pot 518 may be connected to the rear extension 514 to damp the scale chute 502 while spaghetti is poured in.

It should be noted in FIGURE 17 that the upper end of the chute 502 communicates with the dribbler hopper 383 by means of a dribbling wheel 520. The hopper 383 includes a baffle 417 which serves a purpose similar to the baffle 409 in the hopper 381. Additional baffles 419 and 421 are provided in the hopper 383 to allow a predetermined amount of spaghetti to pass thereby. The baffles 419 and 421 alternately rise and fall to allow only that amount of spaghetti which may rest therebetween to pass through. The vertical oscillation of the baffles 419 and 421 is accomplished by the arms 423 and 425 being connected at one end to the baffles 419 and 421 respectively through the links 427. The other ends of the arms 423 and 425 rotate freely about the shaft 429. Each of the arms 423 and 425 have a cam follower 431 in registry with a cam surface 433 (shown only with respect to arm 425). The cam surface 433 rotates with the shaft 435 driven by a hopper timing chain 437 (FIGURE 19) and is dependent upon the rotation of the motor 401 (connection not shown).

The dribbling wheel 520 is rotated about the shaft 444 by the speed reducing gear train 522 (FIGURE 16). The gear train 522 is selectively energized by a magnetic clutch 524 having its input supplied by the motor 401 and the shaft 400 (FIGURE 18) and its output at the gear 526 which is freely rotatable about the shaft 400. The clutch unit may be held stationary by means such as the clamp 528.

Activation of the clutch 524 is caused by the switch 530 associated with the extension 514 of the arm 508. Thus it is seen that when the weight in the chute or bucket 502 is below that as determined by the counter weight 516, the switch 530 is closed thereby activating

the clutch 524 and causing the dribbler wheel 520 to rotate. Rotation of the dribbler wheel causes a few sticks of spaghetti to be dropped into the chute 502. It should be noted that additional switching means are included in series with the switch 530 to inactivate the dribbler wheel 520 except at times when the weighing operation is being utilized. Switch 532 associated with the extension 514 and in conjunction with the additional switching means may be utilized to determine when the volumetrically separated amount of spaghetti from the chute 438 is greater or smaller than that preselected by the counterweight 516. This switch may therefore be utilized to activate one of the solenoids 496 associated with the automatic volumetric separation adjustment. Thus it is seen that if the weight of spaghetti dropped from the chute 538 is greater than that predetermined, the volumetric separator will be adjusted to separate a lesser or larger amount of spaghetti on the next cycle. Continued overweight or underweight separation will cause continued adjustments in the volumetric separator in successive cycles until volumetric separation is more or less than that determined by the counter weight 516 and the switch 532.

An arm 534 which may be used to steady the arm 508 while the spaghetti is being dropped into the chute 502 is further utilized to open the gates of the chute 502. To this end an extension (not shown) on the arm 534 may follow a cam on the shaft 435. The cam operation slightly lowers the arm 534 to clear the arms 508 while the spaghetti in the chute 532 is being weighed. Upon completion of the weighing, the arm 534 may further descend to release the locking means 536 and engage the arm 538. The arm 538 is affixed to a common shaft 540 with one of the gates 542. The gates 542 may be caused to act symmetrically by intermeshed sector gears 544 at one end of the associated shafts (FIGURE 19). Thus it is seen that at a downward motion of the arm 534 the gates 542 are opened and spaghetti is allowed to drop to the next lower chute 546. Springs (not shown) may be used to close the gates 542 after the spaghetti has been dropped.

The chute 546 serves to align the ends of the spaghetti contained therein and to lower the same into the bucket 31 disposed therebelow (FIGURE 17). The chute 546 may be suspended by arms 548 pivotally disposed about the shaft 462 and the arm 550 pivoted about the shaft 379.

Also associated with the chute 546 are cam surfaces 552 which have a generally wedge shaped vertical cross section. Cam surfaces 552 coact with a stud 554 (FIGURE 17) and inner walls coextensive with the edge walls of the chute 546 whereby downward motion of the cam 552 will cause the inner walls of the chute 546 to be moved inward toward the spaghetti contained therein. The cam 552 is affixed to one end of the arm 556 which has its other end affixed to the shaft 558. Also affixed to the shaft 553 are the arms 560 (FIGURE 16) and 562 (FIGURE 17). The arm 560 is resiliently connected to the point 564 to urge the cam 562 downward and consequently the inner walls of the chute 546 inward. When spaghetti is being dropped into the chute 546, the arm 562 coacts with cam on the shaft 379 (the cam is shown generally with other cams as 449) to urge the cam 552 upward. Spring means (not shown) may be used to urge the inner walls of the chute 546 outward when the cam 552 is in its raised position. Thus after spaghetti has been dropped into the chute 546, the edges thereof may be aligned by the resilient force of the cam 552 acting on the edges of the chute.

The chute 546 is lowered into the bucket 31 by arms 548 and 550 either or both of which may be activated by cam on a shaft 379 (not shown).

The spaghetti is maintained in the chute 546 by the intermeshed gates 566 similar to the gates 439 in the chute 438. Each of the gates 566 and an arm 570 are affixed

to a shaft 568 (FIGURE 16). Studs 574 are affixed to the outer ends of the arms 570 and are joined by the spring 572. Vertical adjustable stops 576 and 578 are disposed in registry with the studs 574, one above and the other below the studs. When the chute 546 descends carrying with it shafts 568 and the arms 570, the studs 574 engage the stop 576 thereby causing the gates to be opened. Due to the over center action of the spring with the arms 570 the gates remain in their open position until the chute 546 is again raised and the studs 574 contact the stop 578. While the chute 546 is lowered into the bucket 31, the gates 566 are opened and remain open until the chute is partially withdrawn from the bucket so that the gates may be closed clear of the spaghetti dropped therethrough.

Thus it is seen that the hopper unit first separates an adjustable volumetric amount of spaghetti from the main hopper 381. The separated amount of spaghetti is placed on a scale while its weight relative to a standard is determined. Since the weight of the spaghetti is preselected to be less than standard, additional sticks are added until the weight is brought up to the standard. After being weighed, the spaghetti is dropped into a final chute in which the ends are aligned. The final chute is lowered into the conveyer bucket 31 conveying the wrapping material with it to conform the same to the interior contour of the bucket. While still within the bucket the chute releases the spaghetti into the wrapper.

Longitudinal Fold

FIGURES 20 to 23 show the mechanism utilized for the longitudinal folding operation as shown at D in FIGURE 2. A pair of frame members 473 and 475 are mounted on the framework of the machine as generally shown at 17 in FIGURE 1. Shafts 477 and 479 are journaled in the frame members 473 and 475. The shaft 479 extends through the frame member 473 and on the extended portion is secured a gear 481. Arms 483 and 485 are mounted on the shaft 479 and located between the frame members 473 and 475. A finger shaft 487 is pivotally mounted at the outer ends of the arms 483 and 485. Fingers 489 are located in a spaced arrangement on the rod 487 and extend in a common plane. A sprocket 491 is secured at one end of the shaft 487 and spring urged 491 in a clockwise direction as shown in FIGURE 20. A second sprocket 493 is freely rotatable about the shaft 479 and in registry with the sprocket 491. A chain 495 extends between the sprockets 491 and 493. Also freely rotatable about the shaft 479 and secured to the sprocket 493 is a crank 497. Spring 499 is connected between one end of the crank 497 to a stud 501 on the arm 483. The crank 497 is thereby urged in a clockwise rotation relative to the arm 483 about the shaft 479 as viewed in FIGURE 20.

At the opposite end of the crank 497 is a stud 503 which overlies a detent plate 505 (shown only in relation to left hand arm in FIGURE 20). Extending from the crank 497 is a detent 502 in registry with a stud 504 on the arm 483. The detent plate 505 is connected for downward motion with the cross member 551 described hereinafter.

A toothed rack 507 (FIGURE 21) is retained for vertical movement along the frame member 473 by the guides 509 and 511. The teeth of the rack 507 intermesh with the teeth of the gear 481. A spring 513 is connected between the stationary stud 515 on the frame member 473 to the stud 517 on the rack 507 thereby urging the rack in an upward direction. A drive link 519 is connected to the rack 507 and extends downwardly to a cam actuating mechanism to be described hereinafter.

It will be seen therefore that an upward movement of the rack 507 from the position shown in FIGURE 26 will cause a clockwise rotation of the gear 481 and a consequent clockwise rotation of the arm 483. Since the

crank 497 is spring urged against the stud 504, the crank 497 and the arm 483 and the fingers 489 rotate about the shaft 479 of the finger unit. Upon contact of the stud 503 with the detent plate 505, the crank 497 ceases clockwise rotation. At this point and while the arm 483 is still rotating in a clockwise direction, the crank 497 ceases to rotate the crank arm and its associated sprocket 493 ceases to rotate. Continuous rotation of the shaft 487 about the shaft 493 causes the sprocket 491 to rotate in a counterclockwise manner, as viewed in FIGURE 20. Since the sprocket 491 and the fingers 489 are affixed to the shaft 487, the fingers likewise rotate in a counterclockwise manner, to fold an edge of the wrapping material over the product to be packaged. Upon subsequent descent of the plate 505 with the cross member 551 (to be described hereinafter) the fingers 489 are further pressed against the product.

It is seen therefore that the overall manner of operation of the folding arm 483 is that upon an upward movement of the rack 507, the arm 483 rotates in a clockwise manner and a short time thereafter the fingers 489 rotate in a counterclockwise manner, thereby providing an overall downward and inward movement of the fingers 489.

The fingers 521 on shaft 523 operate in a similar manner upon an upward movement of the rack 508 and drive link 520.

As will be seen in FIGURE 20, fingers 521 are considerably longer than the fingers 489. This is advantageous in packaging of material wherein one side of the wrapping paper may be overlapped against the other. The overlapping portion of the paper as viewed in FIGURE 25 will be presented from the left hand side, thereby permitting additional length of the fingers 521. The additional length of the fingers 521 provides an overlap with the fingers 489 so that the product to be wrapped is held down by fingers completely across the top surface.

Additionally it will be noted in FIGURE 22 that the location of the fingers 489 are in registry with the slots 65, 67 and 69 of the bucket 31 disposed therebelow. Upon viewing of FIGURE 23 it will be noted that the fingers 529 are equally spaced but offset from the fingers 489 whereby the fingers 521 may be accommodated by the slots 71, 73 and 75 of bucket 31 (FIGURE 4).

Referring more particularly to FIGURES 24 and 25 the cam drive mechanism for the longitudinal fold unit is observed. Cam follower arms 527 and 529 are journaled on the shaft 531. The free end of cam arm 527 is pivotally connected to the rack 525 through the link 520. Similarly the cam arm 529 is connected to the rack 507 through the link 519. Cam followers 533 and 535 are connected to the arms 527 and 529 respectively.

A cam shaft 537 is journaled in the bearings 539 on the frame of the machine. Cam drive sprockets 173 and 541 as well as the cams 543 and 545 are affixed to the shaft 537 for common rotation.

In operation rotation of the cam 545 will cause periodic downward motion of the link 519. After each periodic downward motion of the link 519, the spring 513 urges the link 519 and its accompanying rack 507 to move in an upward direction, thereby causing operation of the fingers 489. The operation is similar with respect to the fingers 521 but the period of operation need not be, and the preferred embodiment of the invention is not, the same as will be described hereinafter.

Referring to FIGURE 22, a tack sealing element 547 is shown horizontally disposed between the frame members 473 and 475 by studs 553 slidably engaged in bores 555 through the cross member 551. Collars 557 limit the separation of the tack seal element 547 from the cross member 551. It will be noted that the bottom of the tack seal element is provided with openings 549. These openings have spaced and dimensional relationships similar to the fingers 489 and 523. The height or depth of the openings 549 are somewhat larger than the thickness of the fingers 489 and 521 as viewed in FIGURE 20.

The opposite ends of the cross member 551 are affixed to slides 559 which are slidably engaged in tracks defined by the guides 561. A link 563 is affixed to the lower end of each of the slides 559, for connection to the cam drive mechanism.

Referring to FIGURES 24 and 25, the cam follower arms 565 are secured to the torque shaft 531. Cam followers 567 are affixed to the cam follower arms 565 in registry with the cams 569. The cams 569 are affixed to the cam shaft 537 and rotated as described hereinabove. The end of the cam follower arms 565 are connected to the links 563 for activation of the tack seal element.

In operation the tack seal element 547 is free to fall by its own weight or it may be carried downward by spring action limited only by the collars 557 against the cross member 551. Additionally, the cross member 551 may slide downwardly in a slot defined by the guides 561 limited only by the location of the cam follower arms 565 and the links 563. Upon rotation of the cams 569, the cam follower arms 565 are periodically moved upward. When the cam no longer maintains the arms 565 in an upward position the cross member 551 begins to descend through its guides 561 carrying the tack seal element 547 along with it. Upon reaching a package of product 20 within the bucket 31, the heat seal element 547 will cease downward motion while the cross member 551 may continue to descend. It is thus seen that the only force on the package to be wrapped is the weight of the tack seal element 547, or, if more positive action is desired, by the resilient force of springs.

Referring to FIGURES 24 and 25, there is shown a cam surface 571 having downwardly extending end portions 573 and 575. The cam surface 571 is located on the frame to be in registry with the cam arms 101 associated with the buckets 31. Cam surfaces 571, 573 and 575 serve to force the cam arm 101 upwardly as the buckets 31 approach the side fold unit 17. Forcing the arm 101 upwardly causes the shaft 93 to rotate in a clockwise direction as viewed in FIGURE 1 and thereby rotates the arms 95 and 97 downwardly clear of the bucket surface 59. With this arrangement the area immediately surrounding the buckets 31 is free of obstacles for the performance of the operations at the side fold unit 17.

Longitudinal Seal

Referring to FIGURES 26 to 29, the longitudinal seal unit 19 of FIGURE 1 is shown. Frame members 577 and 579 extend upright from the frames of the intermediate and discharge sections 47 and 49 as shown in FIGURE 1. Slide members 581 are disposed for vertical movement against the frame members 577 and 579 between the guides 583. The cross member 585 is attached to the top of each of the slide members 581 for movement therewith. A longitudinal heat seal unit 587 is disposed 45 below the cross member 585 by the studs 589, slidably engaged in the holes 591. Downward movement of the heat unit 587 with respect to the cross member 585 is limited by the collars 593.

Drive links 595 are pivotally affixed to the ends of the slide members 581.

Referring to FIGURES 24 and 25, the drive links 595 are connected to arms 597 which are affixed to a torque tube 599. Also rigidly affixed to the torque tube 599 or integral with one of the arms 597 is a cam follower arm 601 having a cam follower 603 at one end thereof. A cam wheel 605 is affixed to the cam shaft 537 for rotation therewith and in registry with the cam follower 603. Rotation of the cam wheel 605 causes periodic downward motion of the cam follower 603 and a consequent upward motion of the arms 597 and the drive links 595. When the cam follower 603 contacts a low point on the cam wheel 605, the drive links are allowed to descend thereby bringing with them the cross members 585 and the heat unit 587 under their own weight. Upon contact with the package in one of the buckets 31 below it, the heat unit

587 ceases its descent whereas the cross member 585 and its associated slide members 581 may continue to descend, the holes 591 sliding along the studs 589.

It is seen then, that the longitudinal heat seal unit is retained in its upward position and allowed to fall or descend into contact with the package to be sealed in a periodic manner.

End Fold and Seal

Referring to FIGURES 30 through 35, the end seal unit is shown in detail. End frames 607 and 609 are affixed in an upright position on a frame with the discharge section 49, as shown in FIGURE 1. A pair of torque shafts 611 and 613 are rotatably journaled in the end frame 607 and 609 or within bearings therein. The torque shaft 613 extends through the end frame 607 and has a gear 615 attached thereon. The opposite end of the torque shaft 613 extends through the end frame 609 and has a gear 617 attached thereon. The gear 617 is intermeshed with a gear 619 affixed to the torque shaft 611. A rack 621 is disposed for vertical sliding motion along the end frame 607 between the guides 623 and 625. The lower end of the rack 621 is affixed to a driving link 627 to be connected to the cam drive mechanism to be described presently. Thus it is seen that vertical motion of the drive link 627 causes rotary motion of the shafts 611 and 613.

Arms 629 are secured to the shaft 613 for rotary motion therewith. Arms 631 are secured to the shaft 611 in a similar manner. Additional construction and operation on the arms 631 are similar to that to be described for the arms 629. The ends of the arm 629 opposite the shaft 613 is shaped like a clevis and has a shaft 633 with an attached finger 634 extending therethrough. A collar 635 having a radial bearing 637 is secured to the shaft 633 and located between the clevis in the arm 629, for free rotation therein. A spring 639 is affixed between the bearing 637 associated with the arm 629, and a similar bearing associated with the arm 631 juxtaposed thereto. The construction of each of the arms 629 and 631 are similar, being different only in that the arms 631 are complementary to the arms 629.

A cross member 641 having mounting plates 643 disposed below extends across the tops of the end frames 607 and 609. Affixed to the mounting plates are arcuate cam surfaces 645. As viewed in FIGURE 31, the cam surfaces 645 are concentric about the shafts 613 and 611 respectively. The upper portion of the arcuate cam surface 645 may be substantially flat whereas the lower portion protrudes at 647 toward the end frame 607. The relative location of the cam surfaces 645 are such that when the bearing 637 contacts the upper portion of the cam surfaces 645, the fingers 634 are extended outwardly as viewed in FIGURE 32a.

In the operation of the side fold unit an upward motion of the drive link 627 rotates the shafts 611 and 613 upwardly and outwardly and the shaft 633 downwardly and inwardly. The inward rotation of the shafts 633 cause the bearings 637 to ride on the extended portion of the cam surface 645 thereby causing the finger 634 to rotate about the axis of the shaft 633 inwardly as viewed in FIGURE 32a. Upon subsequent downward movement of the drive link 627, the shafts 611 and 613 rotate downwardly and outwardly and the bearings 637 will follow the cam surface 645 by the action of the spring 639.

Referring to FIGURE 31, a spring 657 is connected between a stud 659 on the end frames 607 and 609, and a similar stud 661 which may be located either on the rack 621 or the drive link 627. It may be seen then that the spring 657 normally retains the rack 621 in the upward position in such a manner that the fingers 634 are extended downwardly and inwardly.

Referring to FIGURES 34 and 35, a cam arm 649 is pivotally mounted about the torque shaft 651. A cam surface 653 on the arm 649 is disposed adjacent to the cam wheel 655. The free end of the cam arm 649 is

pivotedly attached to the drive link 627. Upon rotating the cam wheel 655, the drive link 627 and the connected rack 621 is forced downwardly thereby returning the fingers 634 to their upward and outward position.

The relative location of this unit along the shafts 611 and 613 is such that the fingers when in their downward and inward position press upon the ends of the package to be wrapped disposed in the bucket 31. Consequently, upon operation of the side fold unit, the fingers 634 will descend in a wiping motion to contact the sides of the wrapping material 35 as viewed in FIGURE 2F causing an inward folding.

Referring again to FIGURES 30 through 33, the top fold mechanism is shown. Slides 663 are disposed for vertical movement along the end frames 607 and 609 in the area defined by the guides 665. Since the construction of each of the slides is similar, only one will be described. Extensions 667 and 668 are affixed to the slide 663 and a shaft 669 connects the extensions at the ends opposite the slide. Crank 671 is pivotally mounted about the shaft 669 and disposed between the extensions 667 and 668. A blade 673 and a spring 675 are affixed to one end of the crank 671. The other end of the spring is attached to a point near the end frames 607 and 609 such as the stud 677 mounted between the extensions 667 and 668. A cam wheel 679 is pivotally mounted on the other end of the arm 671.

A cam 681 having cam surfaces 683 and 684 is pivotally mounted to the cross member 641 at 685. A member 687 depends rigidly from the cross member 641 and has a counter-sunk bore 689 at the lower end thereof. A stud 691 attached to the cam 681 passes through the narrow portion of the counter-sunk bore 691 and a spring 693 received by the wider portion of the counter-sunk bore 689, encircles the stud 691. A collar 693 limits the horizontal movement of the stud 691.

Drive links 695 are affixed to the lower ends of the slides 663. Springs 697 are attached between the studs 701 on the extensions 667 and 668 and the stud 669 at the lower end of the guide 665.

Drive links 695 are pivotally attached to the cam arms 703. The other end of the cam arms 703 are secured to the torque shaft 651 for rotation therewith. Cam followers 705 are disposed on the cam arm 703 adjacent the cam wheels 707. The cam wheels 707 are secured to the cam shafts 656 for rotation therewith.

It is seen that the spring 697 retains the extensions 667 and 668 in their downward positions whereby the arms 671 are rotated in a counterclockwise manner (as the left arm 671 is viewed in FIGURE 32a). Upon rotation of the cam wheels 707, the cam arms 703 are moved upward, to cause the links 695 and the slides 663 to carry their associated parts upward whereby the cam wheel 679 is beyond the cam surface 684 to the surface 683. Movement of the cam wheel 679 to the cam surface 683 allows the spring 675 to rotate the arm 671 in a clockwise manner, thereby urging the blades 673 to extend outwardly as viewed in FIGURE 37. In operation then, periodic downward movement of the links 695 causes the blades 673 to travel downwardly and inwardly as viewed in FIGURE 32a.

The parts associated with the top fold unit like those associated with the side fold unit are located within the end frames 607 and 609 such that in their downwardly and inwardly positions they overlie and press against the product within the buckets 31 to be packaged. The spring 693 associated with the cam 684 provides the blades 673 with a resilient force upon pressing against the product to be packaged.

The bottom fold and seal unit shown in FIGURES 30 and 32b serves not only to make the final fold of the package but also to seal the entire ends. A pair of guide members 709 extend downwardly from the frame of the discharge section 49. Slides 711 with integral fulcrum members 713 and 715 are engaged within the guide mem-

bers for vertical movement therein. Shafts 717 extend between the fulcrum members 713 and 715 to provide pivots for the arms 719. The upper ends of the arms 719 carry heat units 721 while the lower end of the arms 719 carry cam followers 723. Springs 725 are disposed between the studs 727 and 729 carried by the slides 711 and the arms 719, respectively, to urge the heat units 721 inwardly. Cams 731 including the cam surfaces 733, 734 and 735 are mounted on the guide members 709 and are disposed adjacent the cam followers 723. Drive links 737 are secured to the studs 725 at one end and to the cam drive mechanism to be described presently on the other.

It will be seen then that upon upward movement of the drive links 737 the heat unit 721 will travel upwardly and inwardly toward a package within the bucket 31. Upward motion of the slides and consequently of the heat units 721 is provided by springs 739 extended between the stationary studs 741 and the arm 745 (FIGURE 34).

Referring to FIGURES 34 and 35, the cam follower arm 743 and the free arm 745 are secured to a common torque tube 747. A cam follower 749 is affixed to the cam arm 743 and is disposed adjacent and below the cam wheel 751 which is secured to the cam shaft 656 for common rotation therewith. The cam arm 743 is parallel to the free arm 745 both of which are periodically forced downward against the spring 739 upon rotation of the cam shaft 656. It is seen therefore that the heat unit 721 will periodically be raised and lowered. It is also seen that while the heat units 721 are in their raised position, they may be pressed against the product within the bucket 31 by passage of the cam followers 723 from the cam surfaces 733 to the cam surfaces 735.

During the operations of the end seal unit 21 it is preferable to retain and reinforce the product to be wrapped so that the package will remain centrally located in the bucket 31 and that too great a force from the members pressing the ends of the package will not cause buckling of the contents. For this reason leaf springs 753 are disposed over the buckets 31 in registry with the front openings 63 and 69 on the buckets 31 and the rear openings 71 and 77. The height of the springs from the bucket 31 is adjustable by means of the studs 755 being adjustably engaged in the clevises 757. The clevises 757 may be secured to any stationary portion of the unit as for instance to the stationary members 687.

The openings in the front and rear walls of the buckets 31 are selected to allow the product to be packaged to be exposed through the openings as viewed in FIGURE 32a. Consequently the springs 753 will exert a resilient force on the product to retain it in a fixed position.

The Dispensing Unit

As viewed in FIGURES 3 and 6, the manner of dispensing the completed packages is shown. As the bucket chain 25 carries the shafts 85 and 87 about the sprocket gears 111 and 113, the longitudinal slot 83 slides about the rear shaft 79 so as to correct the differences in length between the two shafts when the chain is in a straight line and when it conforms to the sprockets. The dispensing unit 23 like the other units of the machine may be a complete station and like the other units the buckets 31 stop for the operation. With the dispensing unit the bucket bars 79 are extended in a vertical position as shown at the right hand bucket in FIGURE 6. Consequently the open face of the bucket extends sidewardly and the packaged material is free to fall into the chute 759 affixed to the frame. A conveyer belt 761 extends about the roller 155 and is disposed below the chute 759 to receive the packages falling therefrom. The other end of the conveyer belt may be disposed about a secondary roller (not shown) at such a point as may be desirable to deliver the packages.

Timing

As has been stated previously, the spacing between

each of the stations is equal or if not equal, the spacing between any two stations will be equal to an integral multiple of the spacing between the closest stations. Likewise, the spacing between the buckets 31 is equal and is equal to the spacing between the two closest stations. With this arrangement each of the stations may operate upon a separate bucket simultaneously. The timing arrangement is such then that each of the stations requires the same amount of time to perform its particular operation except as otherwise noted hereinafter.

The overall timing of the machine is accomplished by the use of the timing chain 169, which engages the various timing sprockets throughout the machine. The sprockets, in turn, rotate the various cam shafts to define the particular timing of each particular element. The timing chain is motivated by the continually rotating output shaft of the speed gear reducer 133.

FIGURES 36 through 40 show the timing charts of each of the individual units of the machine. For each of the units, the timing cycle is equal and may be easily compared with each other by considering each with reference to the motion of the buckets 31.

Referring to FIGURE 36, it will be noted that the buckets remain stationary for the first 240 degrees in the cycle, while from 240 to 360 degrees the buckets move from one station to the next. Additionally the cycle of the machine is such that the shaft 109 (FIGURE 15) rotates thereby pulling the chain 275 and rotating the drive sprocket 273 of the wrapping material feed clutch from 170 degrees to 350 degrees of the cycle. It should be realized that although the drive sprocket 273 is rotating, the wrapping material need not necessarily be fed for the full 180 degrees. As explained previously, the clutch may be disengaged prior to the end of the cycle to cause wrapping material feed at less than 180 degrees of the cycle.

The third timing circle of FIGURE 36 indicates the cycle of the wrapper hold-down arms 95 and 97. As is indicated, the clamp opens while the buckets 31 are stationary. At this time, end portion of the wrapper is between the clamp and the front of the bucket. At 90 degrees of the cycle the arms begin to close and by 120 degrees have completely closed against the wrapper.

The inner timing circle of FIGURE 36 shows the operation of the knife edge 321. It will be noted that the knives cut and begin to retract during the time that the wrapper feed is inoperative. It should also be noted that the knife performs its cutting action after the wrapper clamp is closed to engage the wrapping material 35 against the bucket 31.

FIGURE 37 shows the timing cycle of the hopper unit of the machine. The outer circle *a* indicates the motion of the bucket 31. Circle *b* indicates the timing of the fingers 452 in their movement to and from the center as shown in FIGURE 18. Circle *c* indicates the motion of the side walls 476 (FIGURE 18). As indicated, the side walls are urged toward the center while the fingers 452 are in motion away from the center finger 451. Circle *d* indicates the movement of the fingers 451 and 452 into the chute 438. From the chart it is obvious that the overall action of the fingers 451 and 452 are first to move into the chute and then to spread toward the outer edges, to retract from the edges and to withdraw from the chute. Circle *e* indicates the cycle of the gates 439 to close the chute 438. It is noted that the gates 439 open and the spaghetti is allowed to drop while the fingers are inside the chute 438 and are drawn to their outer extremities.

Circle *f* indicates the cycle of the scale and scale chute. It is noted that the scale is weighing and that the dribble feed is "on" from 335 degrees of a cycle to 155 degrees of the following cycle or a total of 180 degrees. If the scale is not brought up to weight well within this 180 degrees of the cycle, a switch is provided to activate one of the solenoids 495 (FIGURE 18) whereby the volumetric separator is adjusted to separate a slightly greater

or lesser amount in the following cycle. Moreover, if the weight in any particular cycle is still below the standard near the end of the 180 degrees, power to the clutch assembly 131 (FIGURE 5) is cut off by operation of another switch. Consequently the machine is locked up until the weight in the scale is brought up to standard. It should be noted that the vibrating hoppers 381 and 383, the baffles 419 and 421, and the dribble feed wheel 520 are operated by an auxiliary motor 401 (FIGURE 17) which is not affected by the inoperation of the clutch 131. Consequently, small amounts of spaghetti will be continually added to the scale chute 502 until the weight is brought up to standard, at which time clutch 131 is engaged to continue the machine operation.

Circle *g* indicates the cycle of the dump chute 546 in its travel downward to the bucket 31. It should be noted that this travel occurs while the buckets 31 are stationary. Circle *h* indicates the operation of the cam 552 (FIGURE 17) to urge the edge walls of the chute 546 against the spaghetti contained therein.

FIGURE 38 shows the timing chart of the longitudinal folder and tack sealer in comparison with the bucket motion. It should be noted that fingers 521 and fingers 489 (FIGURE 20) both start their motion inward before the beginning of the cycle or in other words, while the buckets are still in motion. It should be understood that while these fingers are in motion they are not in contact with the package within the buckets until the end of their movement inward. Consequently, fingers 489 which is the leading folder, completes contacts with the package as the buckets become stationary, while fingers 521, the trailing folder, completes contact 20 degrees after the bucket has stopped. With this arrangement it is apparent that the leading edge of the package is folded inwardly first and the trailing edge is lapped over the leading edge. It should also be noted that each of the fingers 489 and 521 are further pressed upon goods for tightening purposes and remain in their folded-in position until 205 degrees of the machine cycle.

Shortly after the fingers 521 complete contact with the package, the tack seal unit 547 begins its descent to contact the package, thereby carrying the detent 505 (FIGURE 20) to force the fingers 489 and 521 onto the package. The tack seal remains down until 185 degrees of the cycle has passed and 20 degrees before the fingers move out.

Referring to FIGURE 39 the timing chart of the line sealer is shown. Again it will be noted that the line seal unit begins its descent towards the package before the bucket has stopped. The descent is complete by 35 degrees of the cycle and the sealer remains in contact with the package until 200 degrees of the cycle thereby giving a substantial period of time for the sealing operation to take place. It will be noted that the seal period itself is entirely within the time that the buckets are stationary, however the line seal unit does not complete its ascent until after the buckets have begun their motion.

FIGURE 40 illustrates the timing cycle of the end fold and seal unit. As will be noted, the side fold fingers 634 (FIGURE 30) begin their descent while the buckets 31 are still in motion. While the side fold fingers are still in their descended position, the top folder 673 begins and completes its descent. After the descent of the top folder is complete, the side fold fingers begin their ascent. While the top folder is descending onto the package the bottom folder and end sealer 721 (FIGURE 32b) begins its ascent. While the top folder dwells against the package, the bottom fold and end seal unit 721 is raised to that point where the cam followers 723 reach the upper edge of the cam surface 733. Consequently the folder 721 is near its upward limit but is still retained outward from the package. After the top folder is withdrawn from the package, the bottom folder and end sealer completes its ascent and is urged inward toward the package. By keeping the seal unit 721 relatively withdrawn from the

package until the top folder is free therefrom, no sealing action occurs on that part of the wrapper disposed between the top folder 673 and the bottom folder 721. Consequently when the bottom folder and seal unit 721 is urged toward the package, the sealing qualities of the wrapping material have not been impaired by preheating.

Electrical Circuit

The electrical circuit of the machine is shown in FIGURE 41. A source of alternating current voltage is applied to the machine through the switch 767 from the lines 765 and 766. It will be noted that reference numerals used in connection with the electrical circuit are the same as those used earlier in the specification in connection with the various parts. The several seal units 547 and 587 and 721, (FIGURES 22, 28 and 32b respectively) which may be resistance type heaters are connected across the A.-C. line through their respective fuses and thermostats 768 and 769. A pilot light 770 may be employed to indicate when the machine is on. The main drive motors 121 (FIGURE 3) and the auxiliary drive motors 401 (FIGURE 16) are also connected across the line 765 and 766.

The solenoids 496 (FIGURE 18) are connected across the A.-C. lines through the switches 530 (FIGURE 16) and 771. The switch 771 is a timing switch and like the other timing switches 772 through 775, may be operated by various timing cams affixed to the timing shaft 379 (FIGURE 16). Referring to the timing chart for the hopper unit (FIGURE 37) it is noted from circle *f* the dribble feed is "on" for 180 degrees of the machine cycle. Except for the last few degrees that the dribble feed is on, the switch 771 remains open. Near the end of the dribble feed (or approximately 150 degrees of the machine cycle) the timing switch 771 is closed thereby providing power to the center of switch 530. Switch 530 is arranged such that its lower contact 776 is normally closed to the center contact while the upper contact 77 is normally open. If, at the time switch 771 is closed, the scale in FIGURE 16 is balanced, power is applied to the solenoid *b*. If the amount of spaghetti is not yet up to standard, the switch 530 will have its upper contacts 777 connected to the center contacts to actuate the solenoid *a*. Solenoid *a* is connected to slightly increase the volume of spaghetti separated on the following cycle whereas solenoid *b* is connected to cause slightly less to be separated on the subsequent cycle. On subsequent cycles of the machine, the operation of the switch 530 and 771 is repeated thereby tending to approach an optimum separation by the fingers of the volumetric separator. This optimum is selected to be less than the standard whereby dribbling is required.

Also connected across the A.-C. line is a photoelectric control 773 which supplies voltage to the light source 301 (FIGURE 10). The output 779 of the photocell 303 is connected between the line 780 and the timing switch 772. A full wave rectifier 782 is connected across the A.-C. line and supplies direct current power to the D.-C. lines 780 and 781.

The wrapper clutch 269 (FIGURE 10) is connected across the D.-C. lines 780 and 781 through switches 772 and 773. Power may be applied to the center connection of switch 772 through either the switch 773 or the output of the photocell 303. The photoelectric cell is used to detect marking spots on the wrapping material thereby to provide preselected lengths of the material. At the end of each subsequent cycle, the marking spots are disposed between the light source 301 and photocell 303, thereby preventing current from being applied to the wrapper clutch 269 by the photocell. The timing switch 773 is connected such that during the beginning of the cycle, the contacts are closed and power is supplied to the switches 772. As the cycle progresses, the photocell 301 supplies power to the wrapper clutch through the switch 772. At some point in the cycle after the mark-

ing spot has passed from between the light source 301 and the photocell 303 the timing switch 773 is open. Consequently, the only power supplied to the wrapper clutch 269 is from the photocell 303 and the switch 772. When a subsequent marking spot is interposed between the light 301 and the photocell 303, the source of power to the wrapper clutch 269 is open and the wrapping material feed thereby stops. Timing switch 772 remains closed during the entire portion of the cycle allotted to the wrapper feed.

The main drive clutch 131 (FIGURE 5) is connected across the D.-C. line 780 and 781 either through the path including the switch 415 (FIGURE 17) and the upper contact of the switch 532 (FIGURE 16) or through the switch 775 and the lower contacts of switch 532. Switch 532 associated with the scale has its upper contacts normally open while the lower contacts are normally closed. Consequently if the amount of spaghetti in the scale is not brought up to standard, the upper contacts are closed.

Switch 415 associated with the main hopper 381 is normally closed and is opened only by the interruption of the flow of spaghetti in the hopper. Consequently if the spaghetti flows in the main hopper 381 and if the scale is balanced thereby closing the upper contact of switch 532, power may be supplied to the main drive clutch 131 through the switches 532 and 415. If the weight in the scale is not up to standard, power may then be applied to the main drive clutch through the lower contacts of the switch 532 and the timing switch 775. The timing switch 775 is connected such that its upper contact is closed for the major portion of the machine cycle. However, the upper contact is opened at the end of the dribble feed portion of the cycle (see FIGURE 37, circle f). Consequently if the scale is still not up to standard at the end of the dribble feed cycle, power to the main drive clutch will be cut off until the switch 532 associated with the scale closes its upper contact. Under this condition, not only is the current path to the main drive clutch 131 opened, but power may be applied to a main drive brake 783 (FIGURE 5) to insure that the machine cycle is stopped rapidly.

Dribble clutch 524 (FIGURE 18) is connected across the D.-C. line through the timing switch 774 and the lower contact of the scale switch 532. The timing switch 774 is connected to have its contacts closed during the dribble feed portion of the machine cycle. Consequently during the dribble feed portion of the cycle the clutch 524 is energized but only if the switch 532 associated with the scale has its lower contact closed, indicating that the weight is not up to standard. A pilot light 784 may be connected to indicate its operation.

Summary

Thus it is seen that a novel automatic wrapping machine is provided which is capable of wrapping elongated rigid and semi-rigid products. The machine is capable of providing a sheet of wrapping material of preselected length, separating a preselected volume of the product to be wrapped and subsequently bringing the preselected volume up to a selected weight. Additionally means is provided for wrapping the product and sealing the wrapping material against the product itself.

While the embodiment described hereinabove is the preferred embodiment, various alterations will become apparent to those skilled in the art without departing from the scope of the invention.

Claim:

1. The method of separating a predetermined weight of elongated rigid or semi-rigid product including the steps of vibrating a bulk source of the product, inserting a plurality of fingers into the vibrated bulk, spreading the fingers to align the portions separated thereby, placing the separated portion on a scale, applying small

quantities of the product to the scale, and stopping the supply of small quantities responsive to a predetermined indication of the scale.

2. The method as defined in claim 1 together with the step of adjusting the insertion point of said fingers into the bulk responsive to the indication of the scale at a predetermined time.

3. In a machine of the type described for wrapping elongated rigid or semi-rigid products in cyclic operations, a hopper feed unit comprising a vibrating main hopper communicating with a chute at the bottom thereof, said main hopper being adapted to receive bulk amounts of said product and to convey the same by vibration into said chute, means for separating a preselected volume of said product in said chute, said means for separating the product including means for engaging the elongated product progressively along the elongated dimension thereof, a scale disposed below said chute, means for passing said separated amount of the product to said scale from said chute, said scale means serving to determine when the weight of said product contained therein is up to a standard value, a vibrating secondary hopper and a dribble feed wheel serving to communicate said secondary hopper with said scale, said dribble feed wheel being operable responsive to said scale indication, a conveyer bucket adapted to be disposed in close proximity to said hopper, and means for placing said weighed amount of product into said bucket.

4. Apparatus as defined in claim 3 wherein said means for separating a preselected volume of said product includes a plurality of fingers and means for inserting said fingers into said chute to isolate a portion of the product from the bulk.

5. Apparatus as defined in claim 3 wherein said means for separating a preselected volume of the product is adjustable.

6. In a machine for separating a predetermined volume of elongated rigid or semi-rigid products being in stick form, hopper means for receiving a mass of the product, generally upright chute means serving to receive the product from the hopper means, gate means at the lower end of the chute adapted to be actuated either to close the chute means to retain a quantity of the product in the same, or to open the chute means to permit a quantity of the product to be discharged, separating means adapted to be inserted into the chute means to separate that quantity of the product located between said separating means and said gate means from the product in said hopper means, means for actuating said separating means between inserted and retracted positions of the same, said separating means including means for engaging the elongated products progressively along the elongated dimension thereof.

7. In a machine of the type described for wrapping elongated rigid or semi-rigid products in cyclic operations, a hopper feed unit comprising a vibrating main hopper communicating with a chute at the bottom thereof, said main hopper being adapted to receive bulk amounts of said product and to convey the same by vibration into such chute, means for separating a preselected volume of said product in said chute and for aligning the product along the plane of separation, said last named means including a plurality of fingers and means for inserting said fingers into said chute to isolate and align a portion of the product from the bulk, said fingers, while inserted into said chute, being disposed substantially at mid-point between two opposite edges thereof, and means for drawing a plurality of said fingers through the product to the outer edges of the hopper whereby the product contained therein is positively separated and aligned, a scale disposed below said chute, means for passing said separated amount of the product to said scale from the chute, said scale serving to determine when the weight of the product contained therein is up to a standard value, a vibrating secondary hopper

and a dribble feed wheel serving to communicate said secondary hopper with said scale, said dribble feed wheel being operable responsive to the scale indication, a conveyor bucket adapted to be disposed in close proximity to said hopper, and means for placing said weighed amount of said product into said bucket.

8. In a machine of the type described for wrapping elongated rigid or semi-rigid products in cyclic operations, a hopper feed unit comprising a vibrating main hopper communicating with a chute at the bottom thereof, said main hopper being adapted to receive bulk amounts of said product and convey the same by vibration into said chute, said chute including a front wall, a rear wall, two edge walls and a pair of gates disposed at the bottom, means for retracting said edge walls while the product is being placed into or drawn from said chute, means for separating a preselected volume of said product in said chute and for aligning the product along the plane of separation, a scale disposed below said chute, means for passing said separated amount of the product to said scale from said chute, said scale serving to determine when the weight of said product contained therein is up to a standard value, a vibrating secondary hopper and a dribble feed wheel serving to communicate said secondary hopper with said scale, said dribble feed wheel being operable responsive to the scale indication, a conveyor bucket adapted to be disposed in close proximity to said hopper, and means for placing said weighed amount of product into said bucket.

9. In a machine of the type described for wrapping elongated rigid or semi-rigid products in cyclic operations, a hopper feed unit comprising a vibrating main hopper communicating with a chute at the bottom thereof, said main hopper being adapted to receive bulk amounts of said product and to convey the same by a vibration into said chute, means for separating a preselected volume of said product in said chute and for aligning the product along the line of separation, a scale disposed below said chute, means for passing said separated amount of the product to said scale from said chute, said scale serving to determine when the weight of said product contained therein is up to a standard value, said means for separating and aligning a preselected volume of the product being adjustable responsive to the indications of said scale at a preselected time in the machine cycle, a vibrating secondary hopper and a dribble feed wheel serving to communicate said secondary hopper with said scale, said dribble feed wheel being operable

responsive to the scale indication, a conveyor adapted to be disposed in close proximity to said hopper, a means for placing said weighed amount of said product into said bucket.

- 5 10. In a machine for separating a predetermined volume of elongated rigid or semi-rigid products being in stick form, hopper means for receiving a mass of the product, generally upright chute means serving to receive the product from the hopper means, gate means at the lower end of the chute means adapted to be actuated either to close the chute means to retain a quantity of the product in the same, or to open the chute means to permit a quantity of the product to be discharged, finger means adapted to be inserted into the chute means to separate 15 that quantity of the product located between said finger means and said gate means from the product in said hopper means, means for actuating said finger means between inserted and retracted positions of the same, means for transposing said finger means in a general plane parallel 20 to the general plane of the gate means for effecting alignment of the sticks, said machine being operable in cyclic order, scale means for receiving and weighing the quantity of product discharged from the chute, and means responsive to indication of said scale means for adjusting vertical position of said finger means whereby the volume separated in subsequent cycles approaches a predetermined weight.

11. In a machine as defined in claim 10, dribble means responsive to said scale means for adding additional sticks 30 of said product to said quantity discharged from the chute whereby a predetermined weight of the product is separated.
